J. WISHART.

CARPET.

No. 17,788.

Patented Oct. 11, 1887.

UNITED STATES PATENT OFFICE.

JOSEPH WISHART, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,788, dated October 11, 1887.

Application filed August 30, 1887. Serial No. 248,316. Term of patent 3½ years.

To all whom it may concern:

Be it known that I, JOSEPH WISHART, of New York city, in the county and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is for the border of a carpet, and consists of an inner band having its edges curved so as to form a wavy outline, along 20 which runs a light stem-work bearing small circular flowers and small leaves. The middle portion of the border has an underlying conventional stem-work.

A is a cluster or body of leaves, from which stems project at the top, each stem bearing a small circular flower, and another flower at its 25 upper end with its side to the front. On either side of the figure A are groups of circular flowers of varying size. Here and there other circular flowers are shown. The outer margin of the border is plain in character and is separated from the middle portion by a line of ornamental forms and small flower groups alternately arranged. 30

What I claim as new, and desire to secure by Letters Patent, is— 35

The design for a carpet-border, consisting of the design substantially as shown.

JOSEPH WISHART.
